UNITED STATES PATENT OFFICE.

CATHRINE A. GRISWOLD, OF WILLIMANTIC, CONNECTICUT.

IMPROVEMENT IN SKIRT-SUPPORTING CORSETS.

Specification forming part of Letters Patent No. 56,210, dated July 10, 1866.

To all whom it may concern:

Be it known that I, CATHRINE ALLSOP GRISWOLD, of Willimantic, Windham county, and State of Connecticut, have invented certain new and useful Improvements in Back and Skirt Supporters; and I do hereby declare that the same is described and represented in the following specification and accompanying drawings.

To enable others skilled in the art to make the same, I will proceed to describe its construction and operation, referring to the drawings, in which the same letters indicate like parts in each of the figures.

The nature of this improvement will be understood from the specification and drawings.

The object desired to be attained is to produce a waistcoat made in two parts and clasped or laced together in front and back, and so shaped as to closely, neatly, and easily fit and support the body, and so that when the lacing is tightened the front of the shoulders will be drawn back more or less, as desirable, greatly to the support and comfort of the person; also to support the clothes or skirts, &c., which usually are supported by the hips.

In the accompanying drawings, Figure 1 is a front view. Fig. 2 is a back view. Fig. 3 is a side view. Figs. 4 and 5 show a face and edge view of the stays inclosed in the edges of the garment for securing the two parts together in front, as shown at *a*. (See Fig. 1.)

b are metallic stays secured in the fabric, having eyelet-holes to receive cord or lacing *c*,

by the use of which the upper and the lower portions or ends are properly adjusted to fit the form or wishes of the wearer. *d* is an elastic shoulder strap or band, which passes over the shoulders of the person, and is properly secured at the upper end or corners (back and front) to prevent it from working down from its own tendency or from the weight of clothes. *e* is a waistband having metal eyes secured thereon at suitable intervals, which engage with the hooks, also secured in a proper manner and position upon the waistcoat. Said band *e* shows the manner in which the clothes may be secured to the waistcoat, and thus avoid their weight resting upon the hips, which is tiresome and injurious to health.

By the use of this improvement it is believed health and comfort will be greatly promoted.

I believe I have shown and described the nature, construction, and advantage of this improvement, so as to enable others skilled to make and use the same.

What I claim as my invention, and desire to secure by Letters Patent, is—

A bodice made upon a metallic form opening before and behind, adjustable in the rear, and having shoulder-straps and fastenings for the support of the skirts, all substantially as shown and described.

CATHRINE ALLSOP GRISWOLD. [L. S.]
